UNITED STATES PATENT OFFICE.

REUBEN SLOTE, OF MOUNT VERNON, NEW YORK, ASSIGNOR TO SLOTE & SCHAFFER, A COPARTNERSHIP CONSISTING OF JACOB I. SCHAFFER AND HIMSELF.

DESIGN FOR A BELT BUCKLE.

Application filed December 5, 1928. Serial No. 29,124. Term of patent 3½ years.

To all whom it may concern:

Be it known that I, REUBEN SLOTE, a citizen of the United States, residing in the city of Mount Vernon, county of Westchester, State of New York, have invented a new, original, and ornamental Design for a Belt Buckle, of which the following is a specification, reference being had to the accompanying drawing, forming part thereof.

Figure 1 is a plan view of a belt buckle showing my new design.

Figure 2 is an edge view of the same.

I claim:

The ornamental design for a belt buckle, as shown.

REUBEN SLOTE.
